UNITED STATES PATENT OFFICE.

EMIL O. SUELFLOW, OF OSHKOSH, WISCONSIN, ASSIGNOR TO THE SCHMIT TRUNK COMPANY, OF OSHKOSH, WISCONSIN, A CORPORATION OF WISCONSIN.

TRUNK.

Application filed January 2, 1928. Serial No. 78,737.

My invention relates to improvements in trunks and is particularly concerned with improvements in that type of trunk commonly referred to as a wardrobe trunk.

5 Such trunks usually comprise two body sections, hinged together along adjacent edges. One of the sections contains a plurality of superposed drawers and the other usually contains clothes hangers.

10 The objects of my present invention are: First, to provide novel means for locking the drawers in place in the section in which they are mounted;

Second, to provide means such as described, in which a single lock will lock all of the drawers in their closed position;

Third, to provide a construction, such as described, in which, when one of the drawers is moved to an open position, all the remaining drawers are unlocked; and

Fourth, to provide a construction, such as described, that is simple, economical to manufacture, easy to operate and not liable to get out of order.

25 Other objects of my invention will appear as this description progresses, reference being had to the accompanying drawings, in which:

Figure 1 is a section through the drawer section of a trunk embodying my invention, the wardrobe section of this trunk being shown as thrown back to an open position;

Figure 2 is a view similar to Figure 1, in which the wardrobe section is omitted and 35 in which some of the drawers are shown in open position;

Figure 3 is a detail section taken on line 3—3 of Figure 1;

Figure 4 is a detail section showing, on an 40 enlarged scale, means that I employ for moving the locking mechanism to its inoperative position; and

Figure 5 is a section taken on line 5—5 of Figure 4.

45 Throughout the several views similar reference characters are used for referring to similar parts.

In the embodiment of my invention disclosed herein I have illustrated, in a conventional way, a trunk having a body formed of two sections 10 and 11, hinged together in the usual manner. The section 11 may contain a plurality of clothes hangers 12, slidably mounted upon racks 13. The section 10 55 contains a plurality of superposed drawers

14, 15, 16 and 17 which are slidably mounted upon suitable supports 18 and provided with handles 19 by which they can be withdrawn from the trunk section.

Each of the drawers, with the exception of 60 the upper one, is provided at its rear end with a locking element in the form of a clip 20 having a vertically extending opening for receiving a hook 21 carried by the vertically reciprocating locking bar 22. This bar is 65 slidably supported upon the adjacent wall by means of the guide clips 23. The locking bar 22 has sufficient movement to enable the hooks 21 to be brought into and out of locking engagement with the clips 20, depending upon the position of the locking bar. A lifting bar 24 has one end pivotally connected with the upper end of the locking bar, as shown at 25, and the other end slides freely in a guide clip 26 carried by the upper end 70 of the section in which the drawers are mounted. This lifting bar may be made of spring metal, tending to urge the locking bar 22 downwardly, or it may be more or less rigid. With either type of construction it is 75 preferable to use an auxiliary leaf spring 27 so positioned as to continuously tend to urge the lifting bar downwardly so as to insure the movement of the locking bar to unlocked position.

80 For raising the locking bar to cause the hooks 21 to engage with the locking clips or elements 20, I support an anti-friction roller 28 on the upper edge of the rear end of the upper drawer 17, preferably making 85 use of brackets 29 for this purpose. The anti-friction roller 28 is positioned so that when the upper drawer is pushed into the wardrobe section this roller will engage the lower side or face of the lifting bar 24 and lift it upwardly sufficiently to cause the locking hooks 21 to engage with the locking clips 20 of the drawers, as shown in Figure 1.

It will, of course, be understood that when 100 the upper drawer is moved outwardly to the position shown in Figure 2, the locking bar 22 will move downwardly under the combined influence of the weight of the locking bar and its associated elements and the influence of the spring 27 and the inherent spring tendency of the lifting bar 24, if this latter element is made of spring metal.

105 In order to hold all of the drawers in their locked position, I provide the upper 110

drawer 17 with a key lock 30, of conventional construction, to enable this drawer to be locked to the facing strip 31 depending downwardly from the upper end of the 5 section in which the drawers are housed. When the lock 30 is locked all of the drawers will be held in their locked positions.

While I have described the details of construction of the preferred embodiment of my 10 invention, it is to be clearly understood that my invention is not limited to these details, but is capable of other adaptations and modifications within the scope of the appended 15 claims.

Having thus described my invention, what I claim is.

1. A locking device for the drawers of wardrobe trunks comprising a rigid vertical rod slidable vertically past the inner ends 20 of the closed drawers; sockets on the inner ends of all the drawers but one and rigid projections on said rod for simultaneously entering all said sockets by upward movement; and a lifting device actuated by movement to closed position of the drawer not 25

provided with a socket; said device comprising a resilient supporting bar pivoted to said vertical rod, a horizontal socket in front of said rod and above said drawer for slidably receiving the other end of said bar, 30 and contact means carried by the drawer for raising said bar.

2. A locking device for the drawers of wardrobe trunks comprising a rigid vertical rod slidable vertically past the inner ends 35 of the closed drawers; sockets on the inner ends of certain of the drawers and rigid projections on said rod for simultaneously entering all said sockets by upward movement; and a lifting device actuated 40 by movement to closed position of a drawer not provided with a socket; said device comprising a supporting bar connected to said vertical rod; a socket for slidably receiving the other end of said bar; and contact 45 means carried by the drawer for raising said bar.

In witness whereof, I hereunto subscribe my name this 30th day of December, 1925.

EMIL O. SUELFLOW.
